[57] CLAIM

The ornamental design for a tape measure case, as shown and described.

DESCRIPTION

FIG. 1 is a left elevational view of a tape measure case showing my new design;

FIG. 2 is a right elevational view thereof;

FIG. 3 is a bottom plan view thereof;

FIG. 4 is a top plan view thereof;

FIG. 5 is a front elevational view thereof;

FIG. 6 is a rear elevational view thereof;

FIG. 7 is a right elevational view showing another embodiment of my new design for a tape measure case;

FIG. 8 is a left elevational view thereof;

FIG. 9 is a bottom plan view thereof; and,

FIG. 10 is a front elevational view thereof.

The top plan view and rear elevational view of the alternative embodiment of FIGS. 7-10 are omitted as being identical to FIGS. 4 and 6 of the first tape measure case embodiment. FIGS. 1, 2, 7 and 8 are depicted in a reduced scale.

The broken line showings are for illustrative purposes only and forms no part of the claimed design.
